UNITED STATES PATENT OFFICE

ARTHUR G. BLAIR, OF YONKERS, NEW YORK, ASSIGNOR, BY MESNE ASSIGNMENTS, TO WESTINGHOUSE ELECTRIC ELEVATOR COMPANY, OF CHICAGO, ILLINOIS, A CORPORATION OF ILLINOIS

SIGNALING SYSTEM FOR ELEVATORS

Application filed December 1, 1924. Serial No. 753,061.

This invention relates to elevator signaling systems and generically considered has for its object and purpose to provide an automatic control system for the signals for elevators, 5 which is simple in its construction and more compact in the arrangement of the commutator and other necessary parts than is the case in signaling systems of this character now in general use.

10 It is one of the important objects of my present improvement to provide a very simple form of commutator, which controls the signal lantern circuits, and operating means therefor which may be arranged in either vertical or horizontal position adjacent to the elevator hatchway, and in a relatively small space.

15 In one embodiment of this new commutator, the brushes are mounted in or carried by a single slab or plate of insulating material, mounted and arranged for movement at all times in a single plane or straight line. This arrangement of the brushes minimizes the possibility of short circuiting and also the possible failure or partial failure of the system, due to wearing of the commutator plates or segments over which the brushes move.

20 It is another important object of the invention to provide an improved operating means for the mercury pot relays for restoring the signal which is given upon the operation of a push button or other switch.

25 It is also a further object of my present invention to provide a directional control switch automatically operated from the commutator operating means for controlling the circuit connections to the signals in the "up" and "down" movements of the elevator.

30 I also propose to provide each of the signal lanterns with a relay, said relays being operated from the directional switch and thereby necessitating the use of only a single wire connection with the series of lanterns, thus resulting in an appreciable saving in wire and in the conduit within which the wires are enclosed and which is located in the elevator hatch way.

35 With the above and other objects in view, the invention consists in the improved elevator signal system and in the form, construc-

tion and relative arrangement of its several parts, as will be hereinafter more fully described, illustrated in the accompanying drawings and subsequently incorporated in the subjoined claims.

40 In the drawings wherein I have illustrated one simple and practical embodiment of the invention, and in which similar characters designate corresponding parts throughout the several views,

45 Figures 1 and 1^a are diagrammatic views showing my improved signaling system as applied to two elevators, certain of the wire connections for the commutator for one elevator being omitted in the interest of clearness.

50 Figure 2 is a detail view looking at right angles to Figure 1 and showing one of the commutators and the automatic means for actuating the directional switch.

55 Figure 3 is a detail elevation of the brush holder for the commutator,

60 Figure 4 is a sectional view taken on the line 4—4 of Figure 3,

65 Figure 5 is a sectional view taken on the line 5—5 of Figure 3,

70 Figure 6 is a detail elevation of one of the mercury pot relays on the control board,

75 Figure 7 is an end view thereof,

80 Figure 8 is a detail elevation of the directional switch, and

85 Figure 9 is an end elevation thereof.

90 For purposes of illustration in Figure 1 of the drawings, I have diagrammatically shown two elevators, indicated at 5, which travel in separate hatch ways. It will be understood, however, as the description proceeds, that the signaling system is applicable as well to a bank or series of elevators of greater number.

95 For each of the elevators, there is provided a commutator for the purpose of automatically controlling the signal circuits for the signal lanterns at the various floor landings. This commutator, I have shown in detail in Figures 3, 4 and 5 of the drawings, and in a preferable embodiment thereof, it includes a suitable base 6 of bakelite or other insulating material, upon one side of which there is mounted and secured a plurality of

55

100

series of circuit closing plates or segments. As shown in Figure 1 of the drawings, three series of these segments are operative in the downward travel of the elevator and the other 3 series are operative in the upward travel of the elevator, such connection of the three series of commutator segments in the signaling circuits being automatically effected through the medium of a directional switch 29 to be hereinafter described. On each side of the commutator base, the series of spaced segments 7 are the lantern segments, the next series of segments 8 are the mercury pot segments and the third series of segments 9 are the set back or the restoring segments.

The signal lanterns, shown at 10, are each provided with a relay 11, said relays being respectively connected with the two series 20 of lantern segments 7 of the commutator. With the exception of the signal lanterns on the lower-most and upper-most floors, which are not provided with a relay 11, but have one side of their circuits respectively connected 25 with one of the segments in the respective series of the lantern segments 7. A single feed wire 12 connects the series of lanterns 10 for both the "up" and "down" directions with the directional switch and the series of 30 relays 11 are also connected with said switch by the wire 13.

The commutator brushes hereinafter referred to are mounted in a slab 14 of bakelite or other insulating material, having suitable 35 guides 15 on its opposite edges engaged in grooves or channels 16 in the edges of the base slab 14. However, if desired, any other suitable means for holding the slab 14 in proper relation with the commutator base 40 may be provided. To the lower end of the slab 14, suitable weights indicated at 17, are fixed and a strap or other flexible element 18 is connected to the upper end of said slab, and is trained over a suitable guide 19. This 45 flexible member is connected to a traveling nut 20 on the rotatably mounted worm screw 21. This screw may be conveniently actuated by a flexible connection 22 with the sprocket or sheave 23, which is driven by the elevator mechanism (not shown). The worm screw 21 is reduced at one of its ends and has a switch arm 24 frictionally fitted thereon. This switch arm is adapted for engagement with spaced contact plates 25 which 50 are respectively connected by the wires 26 with the solenoids 27 and 28, mounted upon one side of the base of the directional switch generally indicated at 29. The switch arm 24 is connected by wire 30 and the manually 55 operable switch 31 on the control board with a source of 10 volt current.

The directional switch 29 is provided with two series of mercury pots 31' which are connected respectively with the brushes 54, 55, 56, 57, 58, 59, 60 and 61, one series of such

brushes being provided upon the movable element 14 of the commutator for each series of mercury pots 31' and said brushes respectively engaging upon the "up" and "down" series of wires connecting the mercury pots 70 with the movable brushes and bound together in a movable cable indicated at 62, which moves in the hatchway. The movable switch element is in the form of a plate 32 of suitable insulating material which is pivotally balanced between suitable bearings or supports 33 on the switch base. The spring 34, having its intermediate portion fixed to one of these bearings, is provided with parallel arms equi-distantly spaced from opposite sides of the pivotal axis plate and bearing upon the upper side of said plate. This plate carries two series of circuit closing members 35, adapted to engage in the respective series of mercury pots 31' when the switch plate is 85 in one position. The cores of the electromagnets 27 and 28 are respectively connected, as shown at 36 and 37, to the plate 32 at opposite sides of its pivot.

Upon the control board 39 there is provided a plurality of relays, each of which includes a solenoid coil 40 and an electro-magnet 41. The movable core 42 of the solenoid coil is adapted to engage in a mercury pot 43. These mercury pots on the control board are connected by wire 44' through the switch 44 to a 110 volt feed line. The mercury pot segments 8 of the commutators for the different elevators are connected with the solenoid coils in series with each other through the 100 wires 45, it being understood, of course, that the mercury pots for the "up" and "down" directions are connected with different solenoids.

The field winding of each solenoid is connected by wire 46 with the 10 volt feed line, which is also connected by wire 47, with one winding of the electro-magnet 41. The other winding of the electro-magnet is connected by wire 48 with one of the elevator push buttons 49. These passenger operated switches are connected through wire 49' to the corresponding mercury pots 31' of the reversing switch 29 and to the switch 31. The other winding of the solenoid 40 is connected by wire 50 to one of the set back segments 9 of the commutator. Normally, the core 42 of the solenoid is supported above the mercury pot 43 by a pivoted armature 51 urged by the spring 52 to its normal position, said armature being 115 adjacent to the pole piece 53 of the electro-magnet.

In the elevator car, there is a double pole switch 63 and when this switch is open, all of the signal connections are broken and the circuit is also broken through the solenoids 27 and 28 so that the movable plate 32 of the directional switch assumes a neutral position. The signal lamp 63' is supplied with current through wire 64 connected with one of the 125

mercury pots of the directional switch, and the wire 12 furnishing current to the lanterns 10, is also connected with switch 63. The 110 volt current is supplied to switch 63 through 5 the feed wire 65 and the 10 volt current is supplied to the said switch through the feed wire 66. This switch also supplies 10 volt current through wire 67 to the set back brushes 61 of the commutator.

10 The brush 60 of the commutator closes the circuit through the floor signal lantern and lights the same independently of the push button or other passenger operative switch whenever the car stops at a floor. The brush 15 61, coating with the restoring or set back segments 9 of the commutator, closes the circuit through the solenoid 40 when the car is stopped at a floor and restores the signal.

The lantern relay 11 is energized through 20 the closing of the circuit by the directional switch through one of the mercury pots 31', said relay being energized only when the car is travelling upward in the hatchway, since these relays are connected only to the up side 25 of the commutator. Through the relays therefor the connection is changed from the "down" to the "up" lamps of the signal lanterns 10. By means of the relays I need only employ a single circuit wire connection for 30 both the "up" and "down" lamps. As indicated by the dotted lines in Figures 1 and 1^a of the drawings corresponding mercury pots 31' on opposite sides of the directional switch are connected with the car signal lamp 35 through the wire 64.

At the start of the travel of the elevator car in one direction, upon rotation of the worm screw 21, which moves the commutator brushes through the medium of the nut 20, 40 the switch arm 24 is disengaged from one of the contact members 25 and engaged with the other of said members, suitable stops being provided to limit the movement of the switch arm in one direction and hold said arm stationary during the continued rotation of the screw 21. When the switch arm is thus moved into engagement with one of the contacts 25, one of the solenoids 27 or 28 is energized, as the case may be, so as to engage one 45 or the other series of the circuit closing elements 35 carried by said plate with one of the series of spaced mercury pots 31' for the "up" and "down" side of the signaling circuit. When the switch arm 24 is not engaged with 50 either of the contact members 25, or the operator's switch 63 is open, the circuit is broken through both of the solenoids 27 and 28 and the movable switch plate 32 is held in a neutral position by the spring 34.

55 It will be understood that when the circuit is closed through one of the brushes 61 and one of the set back segments 9 of the commutator, the core of the solenoid 40 is lifted from the mercury pot 43 and is held in such 60 elevated or lifted position by the angular

lower end of the pivoted armature 51, as seen in Figure 4 of the drawings.

In the operation of the signaling system, when one of the push buttons, for instance, the up push button 49a at the fifth floor is operated by a waiting passenger, the electromagnet coil 41' is energized by a circuit from the switch 31, through conductors 46 and 70, electromagnet coil 41', conductor 48', the contact members of push button 49a and conductor 49' to the switch 31. The energization of the electromagnet coil 41' releases the plunger or core 42' of the associated solenoid 40' (see Fig. 6) so that it makes contact with one of the mercury pots which are connected with a common feed line and thereby completes a circuit for energizing the "up" segment 8' on the commutator, which circuit extends from the switch 44 through conductors 44' and 71, mercury pot 43', solenoid core 42' (now disposed in the mercury pot), conductor 45' to the commutator segment 8'. Assuming that the car is approaching the fifth floor in an up direction, then the up brush 55 engages the energized segment 8' 20 and completes a circuit from that segment for flashing the signal lamp 63' in the car to indicate that a stop is to be made and for lighting the lantern at the fifth floor to indicate that the car is to stop at that floor, 25 which circuit extends from the energized segment 8' through up brush 55, and conductor 72, to the junction contact members 73 on the switch 29, one branch extending through conductor 74, commutator segment 7', conductor 75, contact segment 7", conductor 76, the up lantern at the fifth floor, conductor 12, the contact members 77 on the switch 63, and conductor 65, to the switch 44; and the other branch extending from the junction contact members 73 through conductor 64, the signal lamp 63' and conductor 65 to the switch 44.

Thus it will be seen that when the brushes 54 and 55 of the commutator make contact with the different segments in the movement of the elevator, they close the signaling circuit and light the floor lantern and the signal lamp two floors in advance of the car reaching such floor, the following brushes 56 and 57 and 58 and 59 maintaining the lantern lit until the car reaches such floor.

From the foregoing description, my improved signaling system and its manner of operation will be readily understood. By the provision of the commutator, having the brush holder arranged for movement in a single plane, said brush holder with the base on which the commutator segments are mounted, may be very compactly arranged and positioned adjacent to the elevator hatchway in a minimum space and where said commutator will be easily accessible. The switch actuated by the means for moving the brush holder and which in turn controls the 125

operation of the directional switch, may also be arranged adjacent to the hatchway in either a vertical or horizontal position. By the provision of this directional switch controlling all circuits for the signal lanterns, it will be seen that when the connection with the source of current is broken, all circuit connections with the lanterns are also instantly broken. This will effectually prevent the occurrence of false signals, which sometimes happens in the use of elevator signal systems as now employed. These features in connection with the new mercury pot relays on the control board, provide an elevator signaling system of a very simple character, and one which may be easily and quickly installed.

I have herein referred to an embodiment of my present improvements which I have found to be very satisfactory in practical operation. Nevertheless, it will be understood that the present disclosure is susceptible of embodiment in various other alternative embodiments, and I therefore reserve the privilege of resorting to all such legitimate changes in the form, construction and relative arrangement of the various elements as may be fairly embodied within the spirit and scope of the invention as claimed.

30 What I claim is:—

1. In an elevator signaling system having a commutator provided with a series of "up" and "down" circuit closing segments and brushes movable thereover, a directional switch having "up" and "down" series of circuit making contact members, circuits electrically connecting said contact members with the corresponding series of commutator segments, a movable switch member, two series of circuit closing elements disposed on said member for cooperation with said contact members, means normally maintaining said member in a neutral position for holding open the circuits closable by the elements carried thereby, and electrically controlled means for actuating said movable switch member to alternately engage said elements with the two series of contact members upon reversal of the travel of the elevator car.

50 2. In an elevator signaling system having a commutator provided with "up" and "down" series of circuit closing segments and brushes to travel thereover, a directional switch including two series of contact members, circuits for electrically connecting said contact members with the corresponding series of commutator segments, a pivotally mounted switch member, two series of circuit closing elements disposed on said member for cooperation with the respective series of contact members, means yieldingly retaining said member in a neutral position for holding open the circuits closable by the elements carried thereby, electrically controlled 60 means operatively connected with said mem-

ber at opposite sides of its pivotal point, and means for energizing said electrically controlled means to pivotally move said member in relatively opposite directions upon reversal of the travel of the elevator car and alternately engage the series of circuit closing elements carried by said member with the corresponding series of switch contacts.

3. In an elevator signaling system having a commutator provided with "up" and "down" series of circuit closing segments and brushes to travel thereover, a directional switch including two series of contact members, circuits for electrically connecting the contact members with the corresponding series of commutator segments, a pivotally mounted switch plate, a series of circuit closing elements disposed on said switch plate at each side of its pivotal point for cooperation with the respective series of contact members, a spring having independently acting end portions engaged with the switch plate at opposite sides of its pivotal point to yieldingly hold the same in a normal neutral position for holding open the circuits closable by the elements carried thereby, a reversing switch controlled by reversal in direction of movement of the car, and electrical means controlled by the reversing switch cooperating with said switch plate at opposite sides of its pivotal point to alternately engage the circuit closing elements thereof with the two series of switch contact members upon reversal of the travel of the elevator car.

In testimony that I claim the foregoing as my invention, I have signed my name hereto.

ARTHUR G. BLAIR.
